(57) **CLAIM**

The ornamental design for a helmet, as shown and described.

DESCRIPTION

FIG. 1 is a top front right isometric view of a helmet showing the design.

FIG. 2 is a bottom rear left isometric view of the helmet of FIG. 1.

FIG. 3 is a front elevation view of the helmet of FIG. 1.

FIG. 4 is a rear elevation view of the helmet of FIG. 1.

FIG. 5 is a left elevation view of the helmet of FIG. 1.

FIG. 6 is a right elevation view of the helmet of FIG. 1.

FIG. 7 is a top plan view of the helmet of FIG. 1; and,

FIG. 8 is a bottom plan view of the helmet of FIG. 1.

The pale gray ghosted areas or low contrast showing of the interior of the helmet represents portions of the helmet that form no part of the claimed design.

1 Claim, 8 Drawing Sheets
